UNITED STATES PATENT OFFICE.

THOMAS M. KENNA, OF NEW HAVEN, CONNECTICUT, ASSIGNOR OF ONE-HALF TO JEREMIAH J. SULLIVAN, OF SAME PLACE.

SAW-FILING MACHINE.

SPECIFICATION forming part of Letters Patent No. 612,423, dated October 18, 1898.

Application filed July 16, 1897. Serial No. 644,833. (No model.)

To all whom it may concern:

Be it known that I, THOMAS M. KENNA, of the city and county of New Haven, in the State of Connecticut, have invented a new and useful Improvement in Saw-Filing Machines, of which the following is a description, taken in connection with the drawings, which form a part thereof, and in which—

Figure 1 is a side elevation of a saw-file embodying my invention; Fig. 2, a longitudinal vertical section through the same; Fig. 3, a detail side view of the arbor; Fig. 4, similar views of the divided collar for the file; Fig. 5, a side elevation of the file proper, and Fig. 15 6 a transverse section of the clamp for the saw.

This invention relates to files for filing saws, and has for its object the construction of a machine for filing saws in which the file is mounted on a revolving arbor and is of helical form, so that the operation may be continued from one tooth of a saw to the succeeding tooth without the interruption of the movement of the machine.

In the drawings, A represents the main frame of the machine, which is adapted to be bolted or otherwise secured to a suitable bed-plate or foundation. Standards B and B' are formed integral with the frame A and have at their upper ends divided journal-bearings 25 30 b and b' for a rotary spindle D.

A cap C, having secured on its under side a flat tension-spring c, is adapted to fit over and be secured to the tops of the standards B and B' to secure the bearings in place and 35 so that the free end of said spring c will bear against the top of the forward bearing b'. A set-screw c² is adapted to pass through the cap C and bear against the spring c, the tension of which is regulated thereby.

40 The spindle D has rigidly mounted near its rear end a band-pulley E, to be operated on by a belt, (not shown,) and near its forward end, outside of the standard B', is rigidly mounted an arbor F, having an annular flange f, formed integral therewith at its forward end, and a peripheral shoulder f', as shown in Figs. 2 and 3. The annular flange f is adapted to receive a divided collar G, formed of two sections g and g', each having an abutment g² and g³, adapted to engage with each other and unite the two parts of the collar G.

The collar G when the two parts are so united has on its periphery a helical-shaped groove g⁴ for the reception of a helical file H, beveled in cross-section. (See Fig. 2.) A plate I is 55 adapted to be mounted on the forward end of said spindle D and bear against the outer edge of said collar G and hold the same against the shoulder f', when it is locked in position by a nut i, screwed on the forward end of said spindle, which is screw-threaded for that purpose. In front of the forward standard B' and formed integral with the frame A is a clamp K for holding the saw to be operated upon, consisting of a block k, having an inclined way k', and a plate L, inclined on its under side to correspond with the way k', so that the upper edge of the plate L when in position is always horizontal. Plate L and block k are secured together by a set-screw l, 70 attached to the block k and passing through a horizontal slot l' in said plate L, thereby allowing the plate L a limited horizontal movement. A flange l' is formed on the inner side of said plate L, parallel to the upper edge 75 thereof, on which the saw is adapted to rest.

In operation the saw O to be filed is placed in the clamp K, and the plate L moved endwise on the inclined way k' to raise or lower the position of the saw to adjust the depth 80 which the operator desires the teeth of the saw to be cut, and the plate L secured to the block K by means of the set-screw l. By means of this adjustment in the clamp holding the saw saws of various widths and teeth 85 of various depths may be operated upon by the file. The saw is free to move in the clamp for the purpose shown hereinafter. The file H is mounted, as shown above, and is brought into position to operate upon the first tooth 90 of the saw. Upon the revolution of the helical-shaped file H on the rotating arbor F the saw is forced endwise in the clamp by the engagement of the file with the tooth, and when a revolution is completed the end of the 95 file will be in position to operate upon the next succeeding tooth upon the further revolution of the arbor. By means of the spring c, bearing on the upper portion of the forward journal-bearing b', the arbor F is allowed a slight play in a direction transverse to its length, so that as the file H is rotated 100

to operate upon the tooth of the saw the spring constantly tends to press it downward into deeper engagement therewith as it files away the edge of the tooth.

5 Having now described my invention, what I claim, and desire to secure by Letters Patent, is—

1. In a saw-file, the combination with a rotary spindle; of an arbor rigidly mounted on said spindle, having an annular flange at its forward end; a divided collar formed of two sections, adapted to be mounted on said flange; a helical-shaped groove formed on the periphery of said collar; a helical-shaped file 15 adapted to be mounted in said groove; and means for rotating said spindle, substantially as described.

2. In a saw-file, the combination with a standard; of a divided bearing in said standard; a rotary spindle journaled in said bearing; a file mounted thereon; means for rotating said spindle; a clamp for holding a saw in position to be operated upon by said file; a cap-plate over said bearing, and a 25 spring between said cap-plate and upper portion of said bearing adapted to hold said file in contact with the tooth of said saw as it is operated upon, substantially as described.

3. In a saw-file, the combination with a 30 helical file; means for rotating said file; a clamp consisting of a block having an inclined way, and a plate adjustably mounted

thereon, for carrying a saw to be operated upon by said file, substantially as described.

4. In a saw-file, the combination with a 35 frame; of forward and rear standards, mounted on said frame; divided bearings in said standards; a rotary spindle journaled in said bearings, having at its forward end a flanged arbor, and near its rear end a rigidly-mounted 40 belt-pulley; a divided collar formed of two sections adapted to be mounted on said arbor; a helical groove formed on the periphery of said collar; a helical file mounted in said groove; means for rotating said pulley and 45 spindle; a clamp consisting of a block having an inclined way, and a plate adjustably mounted thereon, mounted on said frame, for holding a saw in position to be operated upon by said file; a cap-plate over said forward 50 bearing; and a flat spring between said cap-plate and upper portion of said bearing adapted to hold said file in contact with the tooth of said saw as it is operated upon, substantially as described.

55 In witness whereof I have hereunto set my hand, at New Haven, in the county of New Haven and State of Connecticut, this 10th day of July, 1897.

THOMAS M. KENNA.
